UNITED STATES PATENT OFFICE.

WILLIAM BARTHOLOMEW, OF CHICAGO, ILLINOIS, ASSIGNOR TO TROY LAUNDRY MACHINERY COMPANY, LTD., OF CHICAGO, ILLINOIS, A CORPORATION OF NEW YORK.

CUFF-PRESS.

1,151,239.

Specification of Letters Patent. Patented Aug. 24, 1915.

Application filed December 22, 1913. Serial No. 808,215.

To all whom it may concern:

Be it known that I, WILLIAM BARTHOLOMEW, a citizen of the United States, residing at Chicago, in the county of Cook and State of Illinois, have invented certain new and useful Improvements in Cuff-Presses, of which the following is a specification.

5 My invention relates in general to laundry machinery, and more particularly to presses 10 for cuffs, or other articles.

In the operation of laundry presses considerable power is required in order that the requisite pressure may be applied to the articles. The operation of such presses by 15 foot or hand power involves so much physical exertion on the part of the operators as to render their use exceedingly fatiguing. On the other hand, the operation of such presses by mechanical power is likely to involve 20 danger of injury to the operators in case of carelessness in applying the articles to the presses.

The primary object of my invention is to 2 provide a fluid pressure operated press for 15 cuffs, or other articles, which will be so simple in operation as to require no more skill than that possessed by the ordinary laundry employee; which will reduce to a minimum 20 danger of injury to the operator; and which will apply sufficient pressure to the 25 articles to impart to them the desired finish.

A further object of my invention is to provide an improved cuff press which will be efficient in use, simple in operation, and 30 durable in construction.

My invention will be more fully disclosed hereinafter with reference to the accompanying drawings, in which the same is 35 illustrated as embodied in a convenient and 40 practical form, and in which—

Figure 1 is a front elevational view; Fig. 2 a side elevational view looking from the right in Fig. 1; and Fig. 3 an enlarged sectional view through one of the controlling 45 valves.

Similar reference characters are used to 50 designate similar parts in the several figures of the drawings.

In the drawings I have shown a double 55 type of press which permits the alternate pressing operation of the two presses, but as the pressing and operating mechanism are exactly the same for both presses, a description of one will be sufficient. I have

shown my invention as applied to a press of 55 the type covered by Patent No. 1,054,269, granted to me on February 25, 1913. It will, however, be understood that my invention is capable of application to other forms of presses than that covered by my said 60 prior patent.

Reference character A designates a supporting base having a standard B supporting at its upper end pressing heads C having the usual form of steam chests and hot 65 shoes D.

Extending outwardly from the standard B is a bracket E in which is fixed a horizontal shaft F by means of set screws f. Upon the shaft F are mounted oscillatory supports 70 G by means of sleeves g loosely surrounding the shaft. Each of the supports G is provided with a post G' projecting upwardly therefrom upon which is secured a plunger H' located within the lower portion of a 75 cylindrical chamber H. The chamber H comprises upper and lower circular members between which is secured an annular partition h. Secured between the upper and lower surfaces of the partition h and the 80 top and bottom members of the chamber H are two diaphragms K² and K', the latter of which rests upon the plunger H'. Resting upon the upper diaphragm K² is a plunger H² inclosed within the upper portion of 85 the chamber H. The plungers H' and H² are preferably circular and of a diameter slightly greater than the diameter of the opening in the partition h.

A rod G² is secured at its lower end to the 90 plunger H² and is screw-threaded at its upper end to engage an interiorly screw-threaded sleeve L having oppositely disposed arms l' and l² upon which are mounted arms m' and m² of the base portion m 95 of the goods support M. The goods support M is provided with a steam chest and a pad M' conforming in shape to the under surface of the head C, in the usual manner. A handle M² is provided for swinging the 100 support M into and out of vertical alignment with the cooperating head C. The sleeve L is vertically adjustable upon the supporting rod G² by means of adjusting nuts l in the usual manner.

Secured to the rod G² above the plunger H² is a collar N from which project in opposite directions arms n' and n², which are

guided by rods N' , N^2 upwardly projecting from the upper member of the chamber H in order to so connect the chamber with the rod G^2 as to prevent relative lateral movement. The lower member of the chamber H is rigidly connected to the support G by means of rods O' and O^2 connected to oppositely projecting arms o' and o^2 at the top of the support G .

- 10 The support G adjacent the sleeve g thereof, which surrounds the shaft F , is provided with oppositely disposed lugs g' and g^2 , which coöperate with oppositely disposed stops p' and p^2 carried by a sleeve P fixed 75 on the shaft F . The stops p' , p^2 are provided with adjustable stop screws p with which engage the lugs g' and g^2 to limit the oscillation of the support G upon the shaft F and thereby control the outward and inward movement of the goods support M 80 relatively to the coöoperating head C .

In order to more securely support the shaft F each end thereof is surrounded by a bearing F' secured thereto by set screw f^2 , 25 each of such bearings being supported at the upper end of a rod f' which is mounted upon the base A .

R designates a conduit leading from a source of fluid pressure supply, such for 30 instance as a supply of compressed air. Connected with the conduit R by means of a T-coupling is a cross conduit r , at the opposite ends of which are supported valve casings R' . Within each valve casing is a 35 rotary plug S for controlling a supply of fluid pressure to a conduit R^2 communicating through the partition h with the space between the diaphragms K' and K^2 . The valve S may be of any suitable construction, such 40 for instance as that illustrated in Fig. 3.

Connected with the valve stem s is an arm t which is connected by means of a link t' with a lever t^2 rigidly secured at its lower end to a treadle T , the latter being fulcrumed at T' upon the base A . A spring T^2 45 is interposed between the treadle T and the base and tends to swing the treadle into the position shown in full lines in Fig. 2. An adjustable stop screw T^3 at the inner end 50 of the treadle T serves to limit the oscillation of the treadle by the spring T .

U designates a latch for retaining the treadle T in its lower position against the tension of the spring T^2 , such latch being 55 fulcrumed at U' to the base A and provided with a notch u , which engages the adjacent edge of the treadle when the latter is depressed. The upper end u' of the latch overhangs the fulcrum so as to serve as a weight 60 to automatically oscillate the latch into position to engage the treadle.

V designates a conduit leading from a steam supply and which is connected through suitable pipes and couplings with 65 the steam chests of the head C and goods

supports M , in the manner fully described and illustrated in my said prior Patent No. 1,054,269.

W designates a goods supporting table which is mounted upon a rod w adjustably supported in a bracket w' carried by the supporting bracket E .

The operation of my improved press is as follows: Assuming that the goods support is pressing against the overlying head C , as shown in full lines in Fig. 2, and at the right in Fig. 1, and it is desired to withdraw the goods support from contact with the head for the purpose of removing the pressed article and putting thereon another article to be pressed, a downward pressure is applied by the foot to the treadle T , thereby oscillating the valve S from the position shown in Fig. 3 in full lines to that shown in dotted lines, thereby connecting the passage r^2 , which communicates with the conduit R^2 , with the exhaust opening r^3 through the medium of the straight passage s' in the valve. In such position of the valve the passage r' , which communicates with the supply conduit, is closed. The fluid pressure is consequently exhausted from the space between the diaphragms K' , K^2 so that the weight of the goods support 95 forces the plunger H^2 downwardly into contact with the upper surface of the annular partition h , and forces such partition downwardly so that its under surface rests upon the lower plunger H' . In such downward movement of the partition the chamber H 100 of course always moves downwardly with respect to the plunger H' . The goods support thereby drops downwardly out of contact with the head and may be swung outwardly to the position shown in dotted lines 105 in Fig. 2 and in full lines at the left of Fig. 1. The article already pressed may then be removed and another article placed thereon. Immediately upon the depression of the treadle it is automatically retained in such 110 depressed position by the latch U , thereby maintaining the connection with the exhaust of the space between the diaphragms.

After the article to be pressed has been placed upon the goods support, the latter is swung into alinement with the coöperating head and the latch oscillated by the toe of the operator to the position shown at the right in Fig. 1, thereby releasing the treadle so that the spring T^2 oscillates the same to the position shown in full lines in Fig. 2. Such oscillation of the treadle oscillates the valve S to the position shown in full lines in Fig. 3, thereby bringing the passages s' and s^2 therein into registry with the supply port r' , and the port r^2 communicating with the conduit R^2 . Fluid pressure then passes to the space between the diaphragms and first lifts the upper diaphragm until the plunger H^2 engages the under surface of the 125 130

upper member of the chamber H, and then lifts the chamber until the inner surface of the lower member thereof engages the plunger H'. The movements of the two dia-
5 phragms forces the goods support toward the head and exerts the requisite pressure upon the interposed article. After the article has been subjected to the pressure for a sufficient interval to impart to it the
10 desired finish, the treadle is again depressed to actuate the valve and allow the pressure to exhaust from the space between the dia-
15 phragms, after which the goods support is swung out and the article removed there-
from preparatory to placing a new article thereon.

From the foregoing description it will be observed that I have invented an improved fluid pressure operated press, parti-
20 cularly adapted for pressing laundry articles, such for instance as cuffs, but also capable of other uses, in which the pressure is applied to the desired extent without im-
25 posing upon the operator any physical ex-
ertion, other than that necessary to operate the controlling valve. It will be further seen that by my improvement the press may be operated in a simple manner and with-
30 out danger of injury to the operator.

I claim:—

1. In a press of the character described, the combination with a fixed pressure mem-
ber, of a coöperating movable pressure mem-
ber, a diaphragm operatively connected to
35 said movable pressure member for moving the same into and out of engagement with the fixed pressure member, a valve for con-
trolling the supply and exhaust of fluid pressure to and from said diaphragm, a
40 treadle connected to said valve to move the same into supply and exhaust positions, a spring engaging said treadle to move the same in one direction, and a latch for automatically locking said treadle in its de-
45 pressed position.

2. In a press of the character described, the combination with a fixed pressure mem-
ber, of a coöperating movable pressure mem-
ber, a shaft comprising alined sections upon
50 one end of which said movable pressure member is supported, an expandible chamber composed of two diaphragms united at their peripheries interposed between the adjacent ends of the sections of said shaft, plungers
55 fixed to said ends of the sections of the shaft engaging the adjacent diaphragms, and means for supplying and exhausting fluid pressure to and from the space between said diaphragms.

60 3. In a press of the character described, the combination with a fixed pressure mem-
ber, of a coöperating movable pressure mem-
ber, a shaft comprising alined sections upon
65 one end of which said movable pressure member is supported, means for pivotally

supporting the opposite end of said shaft whereby the same may be oscillated to swing said movable pressure member into and out of registry with the fixed pressure member, a diaphragm interposed between the adja-
70 cent ends of the sections of said shafts, means extending around said diaphragm and connected to the adjacent ends of the sections of said shaft to support said sections in alinement, but to permit their relative 75 axial movement, and means for supplying and exhausting fluid pressure to and from said diaphragm.

4. In a press of the character described, the combination with a fixed pressure mem-
ber, of a coöperating movable pressure mem-
ber, a shaft on one end of which said mov-
able pressure member is supported, a plun-
ger secured to the other end of said shaft, a
diaphragm upon which said plunger rests, a
second diaphragm secured to said first dia-
phragm and forming therewith a fluid pres-
sure chamber, a second plunger upon which
said second diaphragm rests, means for sup-
porting said second plunger, means extend-
ing around said diaphragm and engaging
said plungers to support them in alinement,
but to permit their relative axial movement,
and means for supplying and exhausting
fluid pressure to and from the chamber be-
95 tween said diaphragms.

5. In a press of the character described, the combination with a fixed pressure mem-
ber, of a coöperating movable pressure mem-
ber, a shaft on one end of which said mov-
able pressure member is supported, a plun-
ger secured to the other end of said shaft, a
diaphragm upon which said plunger rests, a
second diaphragm secured to said first dia-
phragm and forming therewith a fluid pres-
sure chamber, a second plunger upon which
said second diaphragm rests, means for sup-
porting said second plunger, a partition be-
tween said diaphragms having an opening
therethrough of less size than the surfaces 110
of said plungers which engage said dia-
phragms, and means for supplying and ex-
hausting fluid pressure to and from the
chamber between said diaphragms.

6. In a press of the character described, the combination with a fixed pressure mem-
ber, of a coöperating movable pressure mem-
ber, a shaft on one end of which said mov-
able pressure member is supported, a plun-
ger secured to the other end of said shaft, a
diaphragm upon which said plunger rests, a
second diaphragm secured to said first dia-
phragm and forming therewith a fluid pres-
sure chamber, a second plunger upon which
said second diaphragm rests, means for sup-
porting said second plunger, a casing sur-
rounding said diaphragms and inclosing said
plungers, a partition intermediate of said
diaphragms and rigidly supported within
said casing, said casing serving to limit the 125
130

outward movement of the plungers by said diaphragms, and means for supplying and exhausting fluid pressure to and from the chamber between said diaphragms.

- 5 7. In a press of the character described, the combination with a fixed pressure member, of a coöperating movable pressure member, an oscillatory shaft upon the upper end of which said movable pressure member is 10 supported, means for pivotally supporting the lower end of said shaft whereby said shaft may be oscillated to swing said movable pressure member into and out of registry with said fixed pressure member, said 15 shaft comprising two aligned sections, a cylindrical casing surrounding the adjacent ends of the sections of said shaft, a partition in said casing in a plane transverse to said shaft, diaphragms within said casing

on opposite sides of and secured to said partition, plungers within said casing secured to the ends of the sections of said shaft and engaging the outer surfaces of said diaphragms, the said partition serving as a stop to limit the movement of said plungers 25 toward each other, and the walls of said casing serving to limit the movement of said plungers away from each other, and means for supplying and exhausting fluid pressure to and from the space between said dia- 30 phragms.

In testimony whereof, I have subscribed my name.

WILLIAM BARTHOLOMEW.
